[57] CLAIM

The ornamental design for a portable light, as shown and described.

DESCRIPTION

FIG. 1 is a side elevational view of a portable light showing my new design in open, operative position; FIG. 2 is an end elevational view as seen from the right of FIG. 1;

FIG. 3 is a side elevational view of the portable light in closed, inoperative position;

FIG. 4 is a top view thereof;

FIG. 5 is a bottom view thereof;

FIG. 6 is an end elevational view as seen from the left of FIG. 3;

FIG. 7 is an end elevational view as seen from the right of FIG. 3;

FIG. 8 is a perspective view taken from the top, side and right end of FIG. 1; and

FIG. 9 is a perspective view taken from the bottom and side of FIG. 3.
